HYDRAULIC TRANSMISSION

Walter Ferris, Milwaukee, Wis., assignor to The Oilgear Company, Milwaukee, Wis., a corporation of Wisconsin

Application June 7, 1937, Serial No. 146,784

6 Claims. (Cl. 60—53)

This invention relates to hydraulic transmissions of the type having both the pump and the motor thereof arranged inside a single casing. A transmission of this type has heretofore either had the pump cylinders connected directly to the motor cylinders or had the discharge port of the pump connected directly to the inlet port of the motor and the exhaust port of the motor connected directly to the intake port of the pump.

5 The present invention has as an object to provide a hydraulic transmission in which the hydraulic circuit thereof is externalized so that the motor may be controlled otherwise than by regulating the pump and so that liquid discharged by the

10 pump may be utilized for driving an external motor or for other purposes.

15

A hydraulic transmission constructed according to the invention is illustrated in part schematically and in part in detail in the accompanying drawings in which the views are as follows:

Fig. 1 is an elevation of a transmission in which the invention is embodied.

Fig. 2 is a sectional plan view taken on the irregular line 2—2 of Fig. 1.

Fig. 3 is a transverse section taken on the line 3—3 of Fig. 2.

Fig. 4 is a transverse section taken on the line 4—4 of Fig. 2.

Fig. 5 is a circuit diagram showing an outside motor connected in series with the inside motor and with a control valve in a position to enable the pump to deliver liquid to the inside motor and through it to the outside motor.

Fig. 6 is a view of a part of the circuit shown in Fig. 5 but with the control valve in position to bypass the pump and apply a brake load upon the inside motor.

Fig. 7 is a circuit diagram showing an outside motor connected in series with the inside motor and with a control valve in position to enable the pump to direct liquid first to the outside motor and through it to the inside motor.

Fig. 8 is a view of a part of the circuit shown in Fig. 7 but with the control valve in position to bypass the pump and the outside motor and to apply a brake load upon the inside motor.

The transmission has a pump 1 and a motor 2 arranged in a casing 3 which has one end thereof closed by an end head 4 and the other end thereof closed by an end head 5. Casing 3 is provided intermediate its ends with an integral partition or pintle block 6 which divides the interior of casing 3 into a pump compartment and a motor compartment in which pump 1 and motor 2 are arranged respectively.

Pump 1 and motor 2 have been shown as being of the rolling piston type which, since it is fully illustrated and described in Patent No. 2,074,068, will be but briefly described herein.

Pump 1 has its pistons 7 fitted in cylinders arranged radially in rotatable cylinder barrel 8 which is journaled upon a stationary valve shaft or pintle 9 through which liquid flows to and from the cylinders. Pintle 9 is fixed in pintle block 6, as shown in Fig. 2, and provided near its free end with two diametrically opposed ports 10 and 11, as shown in Figs. 5 and 7, with which each cylinder communicates alternately as cylinder barrel 8 rotates.

Pistons 7 have the outer ends or heads thereof in contact with a thrust ring 12 which extends around cylinder barrel 8 and is eccentric thereto when the pump is delivering liquid. Thrust ring 12 is fixed in a cylindrical thrust member 13 which is rotatably mounted and adapted to be rotated in unison with the cylinder barrel by frictional contact between the piston heads and the thrust ring.

The parts just described are substantially the same in both the pump and the motor. Consequently, the corresponding parts of motor 2 have been indicated by corresponding reference numerals with the exponent "a" added and no description thereof will be given.

In order that the displacement of pump 1 may be varied, thrust member 13 is rotatably supported by two bearings 14 and 15 which are carried by a slide block 16, while motor 2 has its thrust member 13a supported by bearings 14a and 15a which are carried, respectively, by pintle block 6 and by end head 5 so that the displacement of motor 2 cannot be varied.

Slide block 16 is restrained from movement axially of pintle 9 by pintle block 6 and by a plate 17 attached to end head 4, and it is restrained from vertical movement by slide plates or bearings (not shown) carried by casing 3.

The displacement of pump 1 may be varied by shifting slide block 16 transversely of the axis of pintle 9 either mechanically, hydraulically or electrically according to the usual practice. As shown, slide block 16 is adapted to be shifted by means of a screw 18 which is fastened thereto and has a sleeve 19 threaded thereon and restrained from axial movement by a cap 20 attached to casing 3. Sleeve 19 may be rotated by means of a hand wheel 21 fixed thereon, and it may be locked in position by a lock nut 22 threaded upon the outer end of screw 18.

The arrangement is such that by loosening lock

nut 22 and then turning hand wheel 21 in one direction or the other, sleeve 19 will be rotated and move screw 18 outward or inward and thereby shift slide block 16 transversely of the axis of the pintle 9 to change the displacement of pump 1. Then, lock nut 22 may be turned against hand wheel 21 to prevent screw 18 from turning and thereby lock slide block 6 in its adjusted position.

Pump 1 is adapted to be driven by a shaft 23 which is connected to cylinder barrel 8 by means of a flexible coupling 24 and which is journaled in a bearing carried by end head 4 and in a bearing arranged in the end of pintle 9.

Motor 2 is adapted to drive a shaft 25 which is connected to cylinder barrel 8^a by means of a flexible coupling 24^a and which is journaled in a bearing carried by end head 5 and in a bearing arranged in the end of pintle 9^a.

When shaft 23 is rotated in the direction of the arrow shown thereon, pistons 7 will draw liquid into their cylinders from port 11 and discharge it into port 10. When liquid is supplied to port 10^a, it will enter the cylinders communicating therewith and force the pistons 7^a in those cylinders outward, thereby causing cylinder barrel 8^a to rotate shaft 25 in the direction of the arrow shown thereon. Rotation of cylinder barrel 8^a causes liquid to be expelled into port 11^a by the pistons 7^a in the cylinders communicating therewith.

A transmission of this type constructed according to the usual practice would have the discharge port of the pump connected directly to the inlet port of the motor and the exhaust port of the motor connected directly to the intake port of the pump by channels formed in the pintle axially thereof.

According to this invention however, the channels connecting the pump and the motor are brought to the outside of the casing so that the liquid discharged by the pump may be utilized for purposes other than driving the motor and so that the motor may be controlled otherwise than by regulating the pump, for example, so that a brake load may be applied to the motor. To this end, ports 10 and 11 communicate, respectively, with two channels 30 and 31 (Figs. 2 and 5) which are formed in pintle 9 axially thereof, and ports 10^a and 11^a communicate, respectively, with two channels 30^a and 31^a which are formed in pintle 9^a axially thereof.

Pintles 9 and 9^a have been shown as being integral but, in practice, they are made separately and channels 30, 31, 30^a and 31^a are drilled from the large ends thereof into communication with the pintle ports. Then the ends of these channels are plugged as indicated at 32 in Fig. 2, then the large ends of the two pintles are welded together, and then the pintles are pressed into a bore 33 formed in pintle block 6.

Channels 30 and 31 communicate, respectively, with two channels 34 and 35 (Figs. 2 and 3) which extend through the side of pintle 9 and through pintle block 6 to the outside of casing 3. Channels 30^a and 31^a communicate, respectively, with two channels 34^a and 35^a (Figs. 2 and 4) which extend through the side of pintle 9^a and through pintle block 6, to the outside of casing 3. Channel 34 also communicates through a channel 36 (Fig. 3) with the inlet of a relief valve 37 the outlet of which is connected through a channel 38 to channel 35 so that, if the pressure created by pump 1 exceeds a predetermined maximum, relief valve 37 will open and

permit liquid to escape from high pressure channel 34 into return channel 35.

Channels 34, 35, 34^a and 35^a are connected to a distributing block which is arranged upon the outside of casing 3 and provided with such channels and valves as may be required to enable the transmission to perform the functions desired.

For the purpose of illustration, the transmission has been shown in Figs. 1 to 6 as having a distributing block 41 fixed to the outside of casing 3 and provided with a U-shaped channel 42 which connects channel 34 to channel 34^a and with a valve chamber 43 having four annular grooves or ports 44, 45, 46 and 47 formed in the wall thereof and controlled by a valve 48 which is ordinarily provided with means for operating it from a remote point but which, in order to simplify the view, has been shown provided with a handle 49 for operating it manually. In order that valve 48 may be shifted easily, the extreme ends of valve chamber 43 are connected to each other or are drained as indicated by the drain channels 50 and 51 shown in Figs. 5 and 6.

As best shown in Figs. 5 and 6, port 44 is connected by a channel 55 to channel 42, port 45 communicates with an external channel 56 and is connected by a channel 57 to channel 35, port 46 is connected by a channel 58 to channel 35^a and communicates with the inlet of a resistance valve 59 which is arranged in block 41, and port 47 communicates with the outlet of resistance valve 59 and also communicates with an external channel 60 through which liquid discharged by motor 2 may be delivered to an outside motor 61 to drive the same, the liquid discharged by motor 61 being returned to pump 1 through channel 56, port 45 and channel 35.

The transmission shown is particularly adapted for driving two parts of a single machine or two separate machines which are to be driven in unison but not necessarily in synchronism with each other.

For example, motor 2 may be employed to drive a machine or the delivery rolls of a machine, such as a printing press, which delivers material in a substantially constant strip, and motor 61 may be employed to drive a winder roll upon which the strip is wound as it is delivered thereto by the delivery rolls of the machine.

The strip is delivered to the winder roll at a substantially constant linear speed which is determined by the adjustment of pump 1. Since the peripheral speed of a roll increases relative to its rotary speed as its diameter increases, it follows that the rotary speed of the winder roll must be gradually decreased as the strip is wound thereon and that the torque of motor 61 must gradually increase as the strip accumulates upon the winder roll in order to maintain a uniform tension upon the strip. Also, motor 61 must have a high starting torque to overcome the static inertia and friction of the winder roll mechanism.

The apparatus shown schematically in Fig. 5 for varying the speed of motor 61 and for enabling it to have a high starting torque is fully illustrated and described in Patent No. 2,078,268. Since this apparatus forms no part of the present invention, it is deemed sufficient to state herein that motor 61 has its outlet connected by a channel 62 to the inlet of a starting valve 63 which has its outlet connected to return channel 56, and that channel 60 is connected through a choke 64, a resistance valve 65, a channel 66, and starting valve 63 to return channel 56.

After the pressure in channel 60 exceeds a predetermined value, resistance valve 65 will open and then liquid will be bypassed around motor 61 through choke 64, resistance valve 65, channel 66 and valve 63 into channel 56 at a rate which is approximately proportional to the difference between the pressures prevailing in channels 60 and 56, thereby depriving motor 61 of a part of the liquid discharged by motor 2 and causing motor 61 to run at a slower speed. As the roll of material upon the winder roll increases in diameter, the torque exerted by motor 61 will increase with a resultant increase in the pressure in channel 60, thereby increasing the rate at which liquid is bypassed so that motor 61 is gradually decelerated and enabled to maintain a substantially constant tension upon the strip.

In order to make up for leakage losses and to maintain a low pressure at the intake of pump 1, a gear pump 67 is provided according to the usual practice. Gear pump 67 is arranged in a pump chamber which is formed in end head 4 and closed at its inner side by plate 17, and one gear of gear pump 67 is keyed upon shaft 23 as shown in Fig. 2.

Gear pump 67 draws its supply of liquid from a reservoir (not shown) and discharges through a channel 68 and a check valve 69 (Figs. 3 and 5) into a channel 70 which communicates with channel 57. Channel 70 also communicates with a relief valve 71 (Fig. 5) through which liquid discharged by gear pump 67 in excess of requirements is exhausted and which enables gear pump 67 to maintain a low pressure in channel 57 and the channels communicating therewith.

When shaft 23 is rotated in the direction of the arrow and valve 48 is in the position shown in Figs. 2 and 5, liquid will flow from pump 1 through channels 30, 34, 42, 34^a and 30^a to the motor cylinders communicating with port 10^a and cause motor 2 to rotate shaft 25 in the direction of the arrow. The liquid discharged by motor 2 will flow through port 11, channels 31^a, 35^a and 58, port 46, valve chamber 43, port 47 and channel 60 to motor 61 and drive it. The liquid discharged by motor 61 through channel 62 and valve 63 and the liquid bypassed through choke 64, resistance valve 65, channel 66 and valve 63 will flow through channel 56, port 45 and channels 57, 35 and 31 to intake port 11.

When valve 48 is shifted to the position shown in Fig. 6, port 45 is opened to port 44 and port 47 is closed to port 46. The liquid discharged by pump 1 will then flow through channels 30, 34, 42 and 55, port 44, valve chamber 43, port 45 and channels 57, 35 and 31 to intake port 11. Pump 1 is thus bypassed and will deliver no liquid to the motors to drive them.

If the energy stored in the moving parts of the machine driven by motor 2 is sufficient to drive motor 2 and cause it to function as a pump, motor 2 will draw liquid into its cylinders through channels 30^a, 34^a, 42 and 55, port 44, valve chamber 43 and port 45 from channel 57 which is supplied with liquid from gear pump 67 and by the liquid discharged by motor 61. The liquid discharged by motor 2 will flow through channels 31^a, 35^a and 58, port 46, resistance valve 59, port 47 and channel 60 to motor 61 to keep motor 61 running as long as motor 2 continues to run. Resistance valve 59 will resist the discharge of liquid therethrough and thereby exert a brake load upon motor 2 to quickly decelerate it to a complete stop. The liquid discharged by motor 61 will

flow through the above described channels to the intake of pump 1.

If it is desired that motor 2 be at times operated independently of an outside motor which at other times is energized by pump 1, the transmission may be provided with a distributing block having a different arrangement of valves such, for example, as the valve arrangement shown in Figs. 7 and 8 in which a distributing block 75 is shown provided with a control valve 76 and a bypass valve 77 having handles 78 and 79 attached thereto for operating them manually but, in practice, such valves are ordinarily provided with means operating them from a remote point.

Valve 76 is fitted in a valve chamber 80 which has three annular grooves or ports 81, 82 and 83 formed in the wall thereof, and valve 77 is fitted in a valve chamber 84 which has two annular grooves or ports 85 and 86 formed in the wall thereof. The ends of valve chambers 80 and 84 are suitably drained in order to permit the valves to be shifted easily. As shown, the left end of both chambers 80 and 84 are connected to a drain channel 87 and valves 76 and 77 are provided, respectively, with channels 88 and 89 which extend longitudinally therethrough.

When valve block 75 is attached to casing 3, channel 34 communicates through a channel 90 with port 81, channel 35 communicates through a channel 91 with port 82, channel 35^a communicates through a channel 92 with port 83 and channel 34^a communicates through a channel 93 with port 86. In order to simplify the view, channel 93 has been shown as an external channel but, in practice, it is arranged inside of block 75.

Port 85 is connected by a channel 94 to port 81 and by a channel 95 to the inlet of a motor 96 the outlet of which is connected to channel 93 by a channel 97. Channel 91 communicates with channel 70 which communicates with gear pump relief valve 71, and gear pump supply channel 68 communicates through check valve 69 with channel 70 as previously explained. Channel 92 communicates with the inlet of a resistance valve 98 the outlet of which is connected by a channel 99 to channel 91.

The arrangement is such that, when pump 1 is being driven and valves 76 and 77 are in the positions shown in Fig. 7, the liquid discharged by pump 1 will flow through channels 30, 34 and 90, port 81, channel 94, port 85 and channel 95 to motor 96 and drive it. The liquid discharged by motor 96 will flow through channels 97, 93, 34^a and 30^a to motor 2 and drive it. The liquid discharged by motor 2 will flow through channels 31^a, 35^a and 92, port 83, valve chamber 80, port 82 and channels 91, 35 and 31 to the intake of pump 1. The liquid supplied by pump 1 thus drives both of the motors.

If valve 77 is shifted to the position shown in Fig. 8 and valve 76 remains in the position shown in Fig. 7, the liquid delivered by pump 1 through the above described channels to port 85 will flow therethrough through valve chamber 84, port 86 and channels 93, 34^a and 30^a to motor 2 and drive it but motor 96 will remain idle for the reason that it was short circuited by shifting valve 77 to open port 85 to port 86.

If valve 76 is shifted to the position shown in Fig. 8, the liquid discharged by pump 1 will be bypassed through channels 30, 34 and 90, port 81, valve chamber 80, port 82 and channels 91, 35 and 31 back to the pump cylinders. Consequently, both motors are deenergized.

If valve 76 is shifted from the position shown

in Fig. 7 to the position shown in Fig. 8 when the transmission is operating and if the energy stored in the moving parts of the machine driven by motor 2 is sufficient to drive motor 2 and cause it to function as a pump, motor 2 will draw liquid into its cylinders from the pump circuit and discharge liquid through channels 31^a, 35^a and 92, resistance valve 98 and channel 99 into the pump circuit. Resistance valve 98 will resist the discharge of liquid therethrough and thereby function to apply a brake load upon motor 2 only if valve 71 is in the position shown in Fig. 8 and to apply a brake load upon both motors if valve 71 is in the position shown in Fig. 7.

From the foregoing description of two illustrative circuits it will be obvious that, by simply changing the channels and valves in the distributing block, many other circuits may be produced without departing from the scope of the invention as hereafter claimed.

The invention is hereby claimed as follows:

1. A hydraulic transmission, comprising a closed casing, a pump arranged within one part of said casing and provided with an intake port and a discharge port, a motor arranged within another part of said casing and provided with an inlet port and an exhaust port, a distributing block arranged upon the outside of said casing, a fluid channel connecting each of said ports to said block, a motor arranged outside said casing, fluid channels connecting said outside motor to said block, and valve means arranged within said block for short circuiting said pump or directing liquid from said pump to one or both of said motors.

2. A hydraulic transmission, comprising a closed casing, a pump arranged within one part of said casing and provided with an intake port and a discharge port, a motor arranged within another part of said casing and provided with an inlet port and an exhaust port, a distributing block arranged upon the outside of said casing, a fluid channel connecting each of said ports to said block, a relief valve arranged outside said casing, a motor arranged outside said casing, fluid channels connecting said outside motor to said block, and valve means arranged within said block and operable either to direct liquid from said pump to said motors or to bypass said pump and simultaneously direct the discharge from at least one of said motors through said relief valve.

3. A hydraulic transmission, comprising a closed casing, a pump arranged within one part of said casing and provided with an intake port and a discharge port, a motor arranged within another part of said casing and provided with an inlet port and an exhaust port, a distributing block arranged upon the outside of said casing, a fluid channel connecting each of said ports to said block, a second motor arranged outside said casing, fluid channels connecting said outside motor in series with said inside motor, a resistance valve, and valve means arranged within said block for controlling communication between certain of said channels and operable to cause liquid to flow from said pump to said motors in sequence or to short circuit said pump and one of said motors and cause the liquid discharged by the other motor to be directed through said resistance valve.

4. A hydraulic transmission, comprising a closed casing, a distributing block arranged upon the outside of said casing, a pintle block formed upon the inside of said casing integral therewith and provided with a central bore and with a plurality of fluid channels connecting said bore to said distributing block, a pump arranged within said casing at one side of said pintle block and having a central valve shaft or pintle fixed in said bore and provided with intake and discharge passages which communicate with certain of said channels, a motor arranged within said casing at the other side of said pintle block and having a central valve shaft or pintle fixed in said bore and provided with inlet and exhaust passages which communicate with other of said channels, a motor arranged outside said casing, fluid channels connecting said outside motor to said distributing block, and valve means arranged within said distributing block for controlling communication between certain of said channels and operable to either short circuit said pump or to direct liquid therefrom to one or both of said motors.

5. A hydraulic transmission, comprising a closed casing, a distributing block arranged upon the outside of said casing, a pintle block formed upon the inside of said casing integral therewith and provided with a central bore and with a plurality of fluid channels connecting said bore to said distributing block, a pump arranged within said casing at one side of said pintle block and having a central valve shaft or pintle fixed in said bore and provided with intake and discharge passages which communicate with certain of said channels, a motor arranged within said casing at the other side of said pintle block and having a central valve shaft or pintle fixed in said bore and provided with inlet and exhaust passages which communicate with other of said channels, a motor arranged outside said casing, fluid channels connecting said outside motor to said distributing block in series with said inside motor, a resistance valve, and valve means arranged within said distributing block for controlling said motors and operable to direct the discharge from at least one of said motors through said resistance valve.

6. A hydraulic transmission, comprising a closed casing, a distributing block arranged upon the outside of said casing, a pintle block formed upon the inside of said casing integral therewith and provided with a plurality of fluid channels communicating with said distributing block, a pump arranged within said casing at one side of said pintle block and having a central valve shaft or pintle supported by said pintle block and provided with intake and discharge passages which communicate with certain of said channels, a motor arranged within said casing at the other side of said pintle block and having a central valve shaft or pintle supported by said pintle block and provided with inlet and exhaust passages which communicate with other of said channels, a second motor arranged outside said casing, and valve means arranged in said distributing block to control communication between certain of said channels and operable to either bypass said pump or to direct liquid therefrom to one or to both of said motors.

WALTER FERRIS.
